UNITED STATES PATENT OFFICE.

JOHN G. YANCHIK, OF WILKES-BARRE, PENNSYLVANIA.

STEEL TIE.

Application filed April 9, 1926. Serial No. 100,941.

My present invention has reference to a metallic tie, and means associated therewith for effectively clamping railway rails thereon.

5 The object is the provision of a metal tie of a construction which will prevent the same from sinking or longitudinal movement in the road-bed and which has associated therewith rail clamping means of 10 a novel construction which permits of the ready arrangement of rails on the tie and the clamping thereof to hold the rails from vertical or tilting movement but which will provide for the necessary longitudinal movement 15 of such rails incident to the expansion and contraction thereof.

A still further object is the provision of a metal tie and means associated therewith for clamping rails thereon, and wherein the 20 rails is supported and cushioned in a manner that will permit the yielding thereof almost to the extent of that afforded by an ordinary wooden tie.

To the attainment of the above broadly 25 stated objects and others which will appear as the nature of the invention is better understood, the improvement resides in certain novel features of construction, combination and operative association of parts, satisfactory embodiments of which are illustrated by the accompanying drawings.

In the drawings:—

Figure 1 is a sectional view approximately on the line 1—1 of Figure 2.

35 Figure 2 is a top plan view with one of the cover plates removed.

Figure 3 is an end view.

Figure 4 is a detail enlarged sectional view approximately on the line 4—4 of 40 Figure 2.

Figure 5 is a sectional view approximately on the line 5—5 of Figure 4 to illustrate the manner in which the rail engaging clamps are adjusted.

45 Figure 6 is a sectional view on the line 6—6 of Figure 1.

Figure 7 is a plan view of one of the inner side plates or linings for the tie.

50 Figure 8 is a similar view of one of the cross members or partitions.

Figure 9 is a top plan view of one end of the improvement illustrating a modification.

Figure 10 is a sectional view on the line 10—10 of Figure 9.

55 Figure 11 is a sectional view on the line 11—11 of Figure 9.

Figure 12 is a sectional view approximately similar to Figure 11, but showing the wrench engaging the stem of the adjusting element, and the manner in which the spring influenced dogs are brought out of engagement with said elements by the contact of the wrench therewith.

Figure 13 is a bottom plan view of the 65 wrench.

Because of the scarcity of wood a number of railway systems have attempted to make use of composition ties. These ties, however, have been found ineffective inasmuch as the same are susceptible to disintegration by weather conditions and also because the desired yieldability between the rail and the tie cannot be produced. Other systems have attempted to adopt metal ties, but in the majority of instances these ties 70 have been found so weighty and costly in manufacture that they are not in general use. Aside from this, such class of ties with which I am acquainted, do not afford the desired yieldability to the rails. Also because of sinking of ties in road-beds, and the disalignment of the rails incident thereto railway systems have found it expedient to plant or lay their ties on a bed of concrete 75 or similar material.

With my improvement I aim to produce a metal tie which will overcome the defects of other ties of metal constructions, and which is of a nature whereby a smaller number of ties for supporting the rails may be employed than is ordinary.

By reference to the drawings it will be noted that my improved metal tie 1 comprises a box-like body which is open at its top and which has its sides, from points 95 equidistant from its ends, notched or cut-away longitudinally. Thus the top of the central portion of each tie is depressed. Received in and fixedly secured to the sides of the tie 1 there are metal plates 2. These 100 plates have their end portions formed with upstanding enlargements 3 that are centrally notched, as at 4, and the said notches being of a length to receive the base 5 of the rails 6 therein. The plates 2 have straight openings 6' that communicate with the notches 4, and inwardly disposed arcuate openings 7 which merge into the said straight openings 6'. The openings 6' are arranged each at an equi-distant space from the end walls 110 provided by the notches 4.

The plates 2, inward of the enlargements

3, at both their upper and lower edges are notched at spaced intervals, as at 8, and these notches are designed to receive therein lugs 9 formed on and extending from the 5 corners of partition plates 10. These partition plates may be riveted or otherwise secured to the plates 2. Each pair of partition plates provides therebetween a compartment which, for distinction, is indicated 10 by the numeral 11. Passing through suitable openings 12, disposed below and to one side of each of the curved slots 7, there is a bolt member 13, and these bolts preferably have reduced ends which pass through the 15 sides of the tie body 1. Each bolt 13 has a circumferential groove to provide a reduced portion 14 and received in each of the reduced portions of the bolts 13 there is the notched lower edge 15 of a rail clamping 20 member 16. The clamp is removable so that the same can be replaced in case of breakage. The outer or active ends of each of the rail clamps 16 is hooked, as at 17, and this hook is designed to be swung over and 25 frictionally engage with the base flange of the rails 6. There are passed through the inner portion of the body, at the corner of the angle walls below the hooks 17, rod members 18. Each of these rods is received 30 in one of the slots 6' and is movable into the arcuate or curved slot 7 to swing the clamps to rail engaging position, in a manner which will now be described.

Straddling the body of each clamp 16 and 35 pivotally secured to each of the rod members 18 there are the bifurcated ends 19 and 20 of bolt members 21 and 22, respectively. The bifurcated end 20 of the bolt 22 is offset 40 with respect to the longitudinal plane of the said bolt, and both of the bolts pass through openings 23 in the spaced partition plates 10. There is screwed on each of the bolts 21 and 22, at the parts thereof received 45 in the compartments 11, a nut member 24. On the bolts and in contact with the opposite faces of the nut members 24 there are 50 oppositely extending sleeves 25. Each nut is round in plan and has its outer periphery formed with equidistantly spaced notches 26. The sides of the plates 2, at the upper portions 55 thereof which are arranged in the compartments 11, are perforated, as at 27, and these perforations are disposed opposite or in a line with the respective nuts 24. By reference to Figure 5 of the drawings it 60 will be noted that the upper wall of one of the perforations 27 is designed to be engaged by the hooked end 28 of a lever 29, the said lever having pivotally secured thereon a finger 30 to engage with the notches 26 of one of the nuts 24. By swinging 65 the lever in one direction the nut will be screwed home on the bolt, and by virtue of such turning of the nut the bolt will be moved longitudinally through the openings

in the partition to swing the clamp 16 to cause the rods 18 to travel out of the straight slots 6' and into the curved slots 7. It is to be noted that the walls of the curved openings 7 are not struck concentric with the 70 axial center of the pivot bolts 18 so that there will be a wedging engagement between the rods 18 and the walls of the said openings 7 which will more effectively hold the 75 jaw portions of the clamp 16 in rail engagement. Of course, when the position of the lever is reversed the nut may be screwed in an opposite direction to swing the clamps to the position illustrated in Figure 4 of the 80 drawings, and thereby permit of the arrangement of the rails on the tie or the release of old rails which are to be replaced. When the clamps are in proper rail engagement lock nuts 31 may be screwed on the 85 bolts to contact with the partitions 10. 85

Secured on the under face of the tie at the ends and at the center thereof there are flat plates 32 and 33, respectively. These plates project a suitable desired distance beyond the sides of the tie. These plates are 90 designed to rest directly on a concrete foundation on the road-bed and even if such foundation is not employed the plates add materially to the width of the tie and prevent the same sinking in the road-bed. Also 95 a portion of the road-bed is arranged over the projecting edges of the plates which not only prevents the sinking of the tie but the lateral or canting movement thereof.

Secured by the bolts 13 to the sides of the 100 tie and by additional securing means 34 there are the straight ends of angle brace members 35 whose upper ends are flattened and inwardly directed, as at 36. To the ends 36 there are riveted or otherwise secured plates 37 that afford the rest or cushioning plates for the rails 6. The cushioning plates, have their edges opposite the clamp 16, notched, as at 38 so that the 105 clamps may be easily removed, and the top of the tie is provided with a removable cover plate 39 which is preferably made of two sections.

In Figures 9 to 13 I have shown a different means for operating the rail clamp 115 throw members which I have referred to as the bolts 21 and 22. In other respects the construction is similar to that previously described. The throw members in these figures are indicated respectively by the numerals 40 and 41. The shanks of each of the throw members 40 and 41 have their inner confronting faces toothed, thus providing 120 rack bars 42 and 43, respectively. These rack bars are received through suitable bearing openings in the partitions 10' and secured transversely in each of the compartments 11' there are upper and lower plates 44, respectively and between these 125 plates the rack bars 42 and 43 pass. The 130

rack bars are engaged by the teeth of a wheel or nut 45 that has its shaft 46 journaled in a bearing opening in the lower plate 44 and that has a round boss or hub 5 extension 47 that is journaled in the upper plate 44. From the boss there is a frustoconical extension 48 from which extends a square shaft 49. Normally engaging with the teeth of the wheel or nut 45 to hold the 10 same against free turning there are pivotally supported spring influenced dogs 50. The active end of each dog has an inwardly rounded upwardly directed flange or lip 51.

The numeral 52 designates the turning element for the toothed nut or wheel 45. This element has a hollow frusto conical end portion 53 of a size to receive the conical portion 48 of the nut member 45 therein and is also provided with a squared socket 20 54 to receive the squared shaft 49 of the nut and to engage with the sides thereof. The socket is formed on the inner end of the lateral handle portion 55 of the member 52. By providing the member 52 with a conical 25 end 53 the outer periphery of the lateral portion will contact with the curved lips 51 of the spring influenced dogs 50 to swing the same out of engagement with the teeth of the nut 45 and thereby permit of the operating member or handle 52 turning the nut and moving the rack bars longitudinally in either direction, with the result that the rail clamping elements will be swung to rail clamping or rail releasing positions.

My construction and the advantages thereof will, it is thought, be perfectly apparent to those skilled in the art to which this invention relates, when the foregoing description is carefully read in connection with the accompanying drawings. The nature of the invention, however, is such as to necessarily render the same susceptible of changes and modifications and therefore, I am not to be restricted to the details herein set forth 40 and hold myself entitled to all such changes therefrom as fairly fall within the scope of what I claim without departing from or sacrificing any of the advantages of the invention.

Having described the invention, I claim:

1. A metal railway tie, lateral plates extending from the bottom thereof, plates providing rail seats also projecting laterally from the sides of the tie, brace means between the rail seats and tie, and rail engaging clamps mounted for swingable movement in the tie and means for swinging said clamps into rail engagement, for locking the rails on the rail plates.

2. A metal railway tie and means cooperating therewith for supporting and clamping railway rails thereon, including plates extending laterally from the tie and upon which the rails rest, brace means between the plates and the sides of the tie,

swingable rail engaging clamps loosely mounted on the tie, guide means for the clamps, longitudinally movable means pivotally connected with each clamp for swinging the same into or out of rail engaging 70 position and means for locking said longitudinally movable means from movement.

3. A metal rail tie and means cooperating therewith for locking rails thereon, comprising a box-like member, plates on the 75 sides thereof, partitions connected to the plates and providing between a pair thereof a compartment, each of said plates, adjacent to its outer end, having vertical and inwardly inclined pairs of slots, rail clamps 80 arranged in pairs and having hooked rail engaging ends, shaft members passing through the bodies of the clamps and received in the mentioned slots, guide means between the plates and the clamps, a rail 85 supporting plate between each cooperating pair of clamps and extending laterally beyond the sides of the tie, brace means between said plates and tie, longitudinally movable means connected to the shafts and received through the respective compartments and means in the compartments engageable with said members for imparting a longitudinal movement thereto to swing the clamps into or out of rail engagement, 90 and locking means for said longitudinal movable means.

4. A metal railway tie and means cooperating therewith for locking rails thereon, comprising a box-like member, plates on the 100 sides thereof, partitions connected to the plates and providing between each pair thereof a compartment, each of said plates, adjacent to its outer end having vertical and inwardly inclined pairs of slots, rail clamps 105 arranged in pairs and having hooked rail engaging ends, shaft members passing through the bodies of the clamps and received in the mentioned slots, guide means between the plates and the clamps, a rail 110 supporting plate between each cooperating pair of clamps and extending laterally beyond the sides of the tie, brace means between said plates and tie, longitudinally movable means connected to the shafts and received through the respective compartments, means in the compartments engageable with said members for imparting a longitudinal movement thereto to swing the clamps into or out of rail engagement, 115 locking means for said longitudinal movable means and a cover plate for the open top of the tie.

5. A metal tie for railway rails and means cooperating therewith for clamping the rails thereon, said tie having lateral extensions at the base thereof, plates fixed on the inner sides of the tie, having their upper ends notched and provided with spaced pairs of vertical slots which merge into inwardly 120 125 130

inclined slots, partitions arranged in pairs and providing compartments therebetween in the tie, shafts arranged transversely in the tie and having their ends received in the mentioned slots, bolt members between the sides of the tie below and outwardly with respect to the respective shafts, rail clamps, each including a body member having its outer corner hooked inwardly and through which bodies the said shafts pass, means holding the clamp bodies from lateral movement on the shafts, said clamp bodies having lower notches that receive the bolt members therein, brace members secured to the sides of the ties by said bolts, rail plates

arranged between each pair of clamps, extending beyond the sides of the tie and supported by said brace members, members passing through guide openings in the partitions and having forked ends which straddle the respective clamp bodies and are connected to the mentioned shafts, means arranged in the compartments and engaging said members turnable to impart a longitudinal movement to said members to swing the clamps, means for locking the members from movement and a cover plate for the open top of the tie.

In testimony whereof I affix my signature.

JOHN G. YANCHIK.
